CATCH FOR A LUGGAGE CASE

Charles S. Gehrie, Montclair, N. J., assignor to Presto Lock Corporation, Garfield, N. J., a corporation of New Jersey

Application March 1, 1954, Serial No. 29,263

Term of patent 14 years

(Cl. D87—1)

To all whom it may concern:

Be it known that I, Charles S. Gehrie, a citizen of the United States, residing at Montclair, in the county of Essex and State of New Jersey, have invented a new, original, and ornamental Design for a Catch for a Luggage Case, of which the following is a specification, reference being had to the accompanying drawing, forming a part thereof.

In the drawing:

Fig. 1 is a front face view of a catch for a luggage case, showing my new design.

Fig. 2 is a side edge elevational view of the catch;

Fig. 3 is a top end view of the same; and

Fig. 4 is a bottom end of the same.

I claim.

The ornamental design for a catch for a luggage case, as shown.
